UNITED STATES PATENT OFFICE.

EDWARD E. RICHARDSON, OF ELYRIA, OHIO, ASSIGNOR TO THE R. & S. NON-DEFLECTING VALVE COMPANY, OF ELYRIA, OHIO, A CORPORATION OF OHIO.

CARBURETOR.

Application filed February 9, 1921. Serial No. 443,526.

To all whom it may concern:

Be it known that I, EDWARD E. RICHARDSON, a citizen of the United States, and a resident of Elyria, county of Lorain, and State of Ohio, have invented certain new and useful Improvements in Carburetors; and I do hereby declare the following to be a full, clear, and exact description of the same, such as will enable others skilled in the art to which my invention appertains to make and use the same.

This invention relates to carburetors, and particularly carburetors such as are employed in connection with internal combustion engines operated by fuel supplied to the carburetor in the form of a liquid, such as gasoline, and which must be thoroughly mixed with air prior to its admission into the engine cylinders.

It is an object of this invention to construct such a carburetor having a connecting throat or passageway between the needle valve opening and the intake manifold, comprising in part a high velocity mixing space for mixing the atomized particles of liquid fuel and air, which restricted passageway leads to a variable Venturi throttle-valve, which is adapted to be manually operated, or operated by suitable mechanical mechanism, so as to control the amount of the fuel mixtures to the internal combustion engine.

It is a further object of my invention to provide a carburetor which will be adapted for ready starting under unfavorable conditions, such as in cold weather and which will enable the engine speed to be rapidly accelerated.

It is also an object of my invention to provide a carburetor having a minimum number of operating parts which are positively operated, and which are without delicate and uncertain adjustments.

It is also an object of this invention to construct an improved type of carburetor embodying a number of features contributing toward efficient carburetion under all conditions of load upon the engine with which the carburetor is connected, and particularly adapted to supply a rich mixture when acceleration loads are imposed upon the engine.

Other objects of my invention and the

invention itself will be made apparent by reference to the following description, and in which description reference will be had to the accompanying drawings forming a part of this specification, said drawings illustrating a preferred form of my invention.

Referring to the drawings:

Fig. 1 shows a side elevation of a carburetor embodying the principles of my invention.

Fig. 2 is an end elevation of the carburetor illustrated in Fig. 1, with the addition of a hot air jacket.

Fig. 3 shows a top plan view of the carburetor of my invention.

Fig. 4 shows a vertical section taken on the line 4—4 of Fig. 3, the hot air jacket being also shown in this figure.

Fig. 5 is a vertical cross-sectional view taken on the line 5—5 of Fig. 3, looking in the direction of the indicating arrows shown in Fig. 3, with the casing removed and with the throttle valve shutters illustrated in closed position.

Fig. 6 shows a similar section to that shown in Fig. 5, except that the throttle valve shutters are shown in wide open position.

Fig. 7 is a section similar to that of Fig. 5, except that the shutters are illustrated in a first intermediate operative position.

Fig. 8 is a similar view to that of Fig. 5, the shutters being shown in a second intermediate position.

Fig. 9 is a similar view to that of Fig. 5, but with the shutters shown in a third, or more advanced, position of opening.

Fig. 10 is a view similar to Fig. 7, of an embodiment wherein the rod member 29 is omitted.

Referring now to the figures, in all of which like reference characters denote like parts, at 1 I show a float chamber containing the float member 2 (Fig. 4), resting on the surface of the fuel contained in the chamber 1, and which float member is adapted to control the admission of fuel at the valve 3, by means of the lever members 4, whose ends rest upon the float member 2, and which control the lifting of the valve needle 5 to admit more fuel to the chamber 1 whenever the fuel in the chamber is below a predeter-

mined level. An external controlling lever 6 is provided for lifting the needle 5 to "flood" the carburetor whenever this is desired.

5 Leading from the float chamber to the mixing chamber 7 is a passageway 8 of very restricted horizontal cross-section for the flow of liquid fuel to the said mixing chamber, a valve needle 9 being provided to regulate the area of the annular orifice 10 which forms the outlet end of the passageway, said orifice 10 and said needle 9 constituting the outlet 'needle' valve. The passageway 8 is contained in a hollow screw plug 9^a, which 10 is threaded into the carburetor casing wall 11 and is made removable therefrom, so that it may be withdrawn through the opening 12, provided in the said casing, and which opening is adapted to be normally closed by 15 the insertion therein of a threaded plug 13, the lower portion of which, in Figs. 1, 2 and 4, is shown as being broken away.

I provide a plurality of mixing chamber portions, one being the mixing chamber 7, 20 and another being the primary mixing chamber 14, which is annular in shape, and disposed around the end of the valve needle 9, the chamber 14 being also considerably restricted in horizontal cross-sectional area, and said annular chamber 14, communicating 25 with a high velocity mixture channel 15, which leads into the secondary mixing chamber 7, the chamber 7 being in fact a continuation of the channel 15, which is constantly enlarged in transverse cross-section.

The carburetor shown in Fig. 4 is shown in the normal condition of rest which it will assume when the engine is inoperative and in this condition the level of the fuel in the 30 mixing-chamber 7, and even in the interior 16 of the valve needle 9 will be level with that of the fuel in the fuel chamber 1, but when the engine is put into operation the liquid fuel contained in the chambers 7, 14 and in the interior of the needle 9 will be rapidly drawn to the engine cylinders through the engine manifold passages 17, and upwards between the valve shutters 18.

Thereafter, as the engine continues to operate liquid fuel will be drawn by the vacuum created by the engine through the annular orifice 10 into the annular passageway 14, being atomized in the process and at the same time air will pass through the external opening 19 of the needle 9 and through the bore 16 of the needle, and emerge into the annular passageway 14 through a plurality of openings 20 located in the lower portion of the enlarged part of the valve needle 9, the air passing through small openings 20, will attain a considerable velocity when it emerges into the mixing chamber 14, and will meet the atomized particles of liquid fuel emerging 55 from the annular orifice 10 of the needle

valve, each particle of fuel being thus broken up by the inrushing air streams, thus producing a nearly homogeneous mixture of fuel particles and air, so that the mixture will emerge into the mixing chamber 7 as a 70 fog of very finely divided fuel floating in air and traveling at a very high velocity.

I find that by the particular arrangement of passageways herein disclosed, having restricted portions as illustrated and described, 75 I attain a high degree of division of the finely divided particles of fuel, which is very desirable. It will be noted also that the air entering the valve needle 9 by the opening 19 will be pre-heated air led to the 80 opening 19 by the tube 21 carrying hot air from a stove of the ordinary type, disposed in any of the well known ways adjacent the exhaust manifold of the engine, or other source of heat, and which tube is connected to an enclosing casing 22, which is arranged about the chamber 7, the shutter casing 23 and the passageway 17 leading to the intake manifold of the engine. Thus, the wall of the passageway comprising the portions 7, 17 and the intermediate valve portion will be kept warm and all of the air admitted to the mixture will be pre-heated.

Figs. 1, 3, 5, 6, 7, 8 and 9 show the carburetor with the casing 22 removed, for the 95 sake of clearness of disclosure.

I prefer, particularly with the present-day low grade fuels, to pre-heat all of the air entering into the carburetor and I have provided a structure wherein this can be accomplished in a simple way, but my invention in its broader aspects is capable of considerable utility without such pre-heating.

The throttling valve illustrated in the drawings of the preferred embodiment of 105 my invention is of special construction, comprising a pair of shutter members 18 and 18^a, the said shutter members being pivotally mounted at their mid portions in journals, as 24, for the shutter 18, and are operated in opposite directions by means of the lever 25, which operates the shutter 18 directly, and which operates the shutter 18 by means of the meshing teeth 26 between the operating members of the two shutters. 115 The lever 25 with its lower toothed portion 27 comprises the operating member for the shutter 18^a, and the toothed member 28 comprises the operating member for the shutter 18.

It will be seen that when the lever member 25 causes the shutter 18^a to rotate in one direction, shutter 18 will be operated in a reverse direction, thus causing the lower ends of the shutters 18 and 18^a to approach or recede from each other providing a throttle valve which can be closed or opened, as desired.

At the top of the mixing chamber 7 I provide a tightly fitting rod member 29,

which is secured at 30 and 31 in the wall 23 of the passageway, the said rod member 29 having an internally threaded head 32.

The shape of the rod member 29 is capable of considerable variation, according to the degree to which atomization is demanded for the carburetor, or it may be omitted altogether as shown in Fig. 10 for some purposes, such as for instance, when extremely rapid acceleration is required, beyond that which can be had when the rod member 29 is in place. The presence of the member 29, which is spaced slightly from the walls 33 and 34 of the mixing chamber 7, causes the fuel mixture to be still further broken up before it enters the passageway restriction occasioned by the partial closure of the shutters 18 and 18^a, when these are in less than wide-open position. It will be noted that the shutter members 18 and 18^a are adapted to perform the function of a venturi in the passageway leading from the chamber 7 to the upper passage 17, the degree of restriction presented to the mixture rushing therethrough being variable according to the degree of opening of the said shutter members.

Thus I have provided, in effect, a variable Venturi mechanism, the same operating without deflecting the mixture against the side walls of the passageway, where portions would condense, were this done. I find that by directing the mixture through the combination venturi and throttling valve mechanism of my invention a high efficiency results, both as to acceleration and fuel consumption and engine performance.

Referring to Figs. 5, 6, 7 and 8, in particular, it will be noted that Fig. 5 shows the valve shutters in closed position, which may be that position wherein no gaseous mixture at all will pass from the carburetor to the engine, or the shutter ends may be so formed or spaced from the member 29 that a certain amount of the mixture will be passed through the valve in order to permit idling of the engine at low speed.

Referring to Fig. 7, this figure shows the valve shutters 18 and 18^a in opened condition, whereby the engine will be permitted to receive a sufficient quantity of fuel to cause it to operate at a relatively high rate of speed. In this position the amount of air admitted to the mixture through the interior of the valve needle member 9 is augmented by air streams flowing into the passageway between the shutters, said air streams flowing from either side upwards between the lower curved ends of the shutters and the adjacent upper edges of the walls 33 and 34 of the mixing chamber 7. These air streams first envelop the mixture streams and then the mixture is diluted as the combining streams mix in their upward path, this

action being started in the lower space between the shutters, and continuing upwards towards the engine intake manifolds.

When the shutters are in the position shown in Fig. 8, still more air is admitted, as before described, from below the ends of the shutters.

When the shutters are in the position shown in Fig. 9, other air streams will enter the mixture through the serrations in the upper outer edges of the shutter, these additional air streams being augmented further, as in the case of the first admitted air streams, when the shutters are in more advanced or full open position, such as shown in Fig. 6.

I find that this means of controlling the mixing of the fuel and air is very efficient in practice, and that the arrangement of parts hereinbefore described contributes to a very high efficiency of fuel combustion in the engine cylinders at varying engine speeds.

Having thus described my invention, I wish it to be understood that the carburetor construction herein illustrated and described is but one of a number of constructions in which my invention may be embodied, I being aware that numerous and extensive departures may be made from the embodiment herein illustrated and described, but without departing from the spirit of my invention.

What I claim is:

In a carburetor, the combination with a mixing chamber, of a fuel jet at the approach end of the chamber, and a throttle valve intermediate the ends thereof, said chamber having a discharge portion of gradually enlarged cross section towards its discharge end, and an approach portion of gradually enlarged cross-section towards its discharge end, a pair of movable valve plates constituting opposite walls of said chamber, spaced parallel trunnions carried in the intermediate walls thereof, supporting the plates at their mid portions and rotatable to cause adjacent ends of each of said plates on the approach side of the valve to meet to practically obstruct the passage through the chamber, or to move outwardly to variably open the passage therethrough, said approach portion terminating in a narrow outlet presented to the meeting ends of said rotatable valve plates but spaced therefrom, said chamber discharge portion presenting its inlet end to the other ends of said plates, but spaced therefrom, whereby air is supplied to the fuel mixture in the chamber around the ends of the plates.

In witness whereof, I have hereunto signed my name this 31st day of January, 1921.

EDWARD E. RICHARDSON.
